UNITED STATES PATENT OFFICE.

WILLIAM W. SWEETLAND, OF EDWARDSBURG, MICHIGAN.

SASH-SUPPORTER.

No. 873,186.

Specification of Letters Patent.

Patented Dec. 10, 1907.

Application filed December 11, 1906. Serial No. 347,349.

To all whom it may concern:

Be it known that I, WILLIAM W. SWEETLAND, a citizen of the United States, residing at Edwardsburg, in the county of Cass and 5 State of Michigan, have invented a new and useful Sash-Supporter, of which the following is a specification.

This invention relates to a sash supporter of that type comprising a rod and a lock arranged one on the window frame and the other on the sash, so that the latter can be locked closed or locked in any desired open position and in such a way as to prevent the sash from being opened from the outside.

15 The invention has for one of its objects to improve and simplify the construction and operation of sash fasteners of this type, so as to be comparatively easy and inexpensive to construct, and reliable and efficient in use.

20 A further object of the invention is to provide a lock comprising a pair of oppositely acting dogs which are adapted to grip the rod of the sash supporter and adapted to be released by levers having thumb pieces arranged to be compressed toward each other and so held while the sash is moving in one 25 direction or the other.

With these objects in view, and others, as will appear as the nature of the invention is 30 better understood, the invention comprises the various novel features of construction and arrangement of parts, which will be more fully described hereinafter and set forth with particularity in the claims appended hereto.

35 In the accompanying drawing, which illustrates one of the embodiments of the invention, Figure 1 is a fragmentary front elevation of a window showing the sash supporter applied to one of the sashes thereof. Fig. 2 40 is a longitudinal section of the lock of the supporter showing the dogs thereof in gripping relation. Fig. 3 is a similar view showing the dogs released. Fig. 4 is a perspective view of the casing of the lock. Figs. 5 and 45 6 are perspective views, respectively, of one of the jaws and releasing levers.

Corresponding parts in the several figures are indicated throughout by similar characters of reference.

50 Referring to the drawing, 1 designates a window frame and 2 one of the sashes thereof. On the window frame is arranged the rod member 3 and on the sash is arranged the lock member 4 of the sash supporter or 55 fastener. While this arrangement is preferable, it is obvious that the rod 3 may be se-

cured to the sash and the lock member to the window frame. Although only one sash is shown equipped with the fastener, it is to be understood that both sashes of the window 60 may, if desired, be provided with separate fasteners. The rod 3 is threaded at the ends 5 and extends through apertured brackets 6 which are secured to the window frame by a screw 7, or other fastening. The rod is held 65 in place in the brackets by nuts 8 screwing on the said threaded ends. The rods and brackets may be made of any suitable metal, and the rod is preferably of round cross section.

70 The lock member of the fastener comprises preferably a cast metal casing 9, of rectangular or box-like form, having base extensions 10 provided with countersunk apertures 11 for receiving screws 12 to secure 75 the casing to the front surface of one of the stiles 13 of the sash 2. The top and bottom walls of the casing are provided with alining openings 14 through which the rod 3 passes. Arranged in the casing are dogs 15 suitably 80 spaced from each other and provided with apertures 16 forming biting edges 17, and through these openings passes the rod 3. The opening 16 of each dog is arranged adjacent one end thereof, and between the dogs 85 may be arranged a spring normally holding the dogs apart, so that the biting edges 17 will grip the rod 3. In the present instance, this spring takes the form of a wire helix 18 wound around the rod 3 and abutting at its 90 ends the dogs 15. The ends of the dogs opposite from the apertures 16 rest in recesses 19 which form fulcrums for the dogs. These recesses are formed on the interior of the side wall 20 of the casing. In the opposite side 95 wall 21 are arranged elongated recesses 22 the ends of which form stops for limiting the movement of the dogs. The dogs are released by levers 23 disposed at the top and bottom of the casing 9, the outer ends of the 100 lever extending through the slots 24 in the side wall 20 and terminating in fingerholds 25. The inner ends of the levers or actuators 23 are perforated at 26 for receiving the rod 3, and the said ends are fulcrumed in 105 recesses 27 in the side wall 21. Extending from each lever is a lug 28 which bears against the adjacent dog. The slots 24 are of sufficient dimension to permit the levers to be compressed toward each other by taking 110 the fingerholds 25 between the thumb and first finger of one hand and applying pres-

sure. By compressing the levers, the dogs are moved toward each other against the tension of the spring 18, so that the biting edges 17 will be moved out of gripping relation 5 with the rod 3, thereby permitting relative movement between the rod and lock of the fastener. As soon as pressure is removed from the fingerholds, the levers return to their normal position, as do also the dogs by 10 reason of the expansion of the spring, so that the biting edges 17 will take hold of the rod.

From the foregoing description, taken in connection with the accompanying drawing, the advantages of the construction and of the 15 method of operation will be readily understood.

In operation, the sash is either raised or lowered by first compressing the fingerholds 25 toward each other and, while they are held so compressed, the sash is moved in the desired direction. When the required point is reached, the fingerholds are released, thereby causing the locking member to firmly grip the rod of the fastener. The sash is 25 thus held in fixed position, and cannot be raised or lowered by power being applied directly to the sash. The spring 18 holds the dogs in positive engagement with the rod 3 so that jolting or vibration of the window 30 does not cause the sash to slip. In view of this fact, the sash supporter is of particular value for car windows. The sash fastener or supporter is easily operated at all times and is of simple and substantial construction and 35 reliable in preventing relative movement of the two members to which the fastener is applied. While the rod 3 has been shown in a vertical position, it is obvious that a fastener may be used between two members 40 that are movable in other directions than the vertical.

I have described the principle of operation of the invention, together with the device which I now consider to be the best embodiment thereof, but I desire to have it understood that the apparatus shown is merely 45 illustrative, and that various changes may

be made, when desired, as are within the scope of the invention.

What is claimed is:—

1. The combination of two relatively movable members, with a fastening device between them, said device comprising a rod secured to one of the members, and a lock secured to the other member, the lock including a pair of dogs having apertures whose edges grip the rod, and actuators independent of the dogs for releasing the latter. 50

2. The combination of two relatively movable members, with a fastening device between them, said device comprising a rod secured to one of the members, a support on the other member, walls on the support disposed in parallel relation and having recesses in their opposed faces, a pair of dogs having gripping means at one end and fulcrumed at their opposite ends in the recesses of one wall, levers disposed alongside of the dogs and fulcrumed in the recesses of the opposite walls, handholds on the levers, and a spring 60 disposed between the dogs. 65

3. The combination of a casing having apertures in its end walls and slots in one of its side walls and recesses on the opposed faces of both side walls, a rod extending through 75 the apertures of the end walls, a pair of dogs in the casing engaging at their ends in certain of the recesses of the side walls and having apertures for receiving the said rod, levers extending through the slots of one of the side 80 walls and fulcrumed in the remaining recesses of the other wall, fingerholds on the outer ends of the levers, devices on the levers extending toward the adjacent dogs and bearing against the same, and a spring arranged 85 between the dogs to normally hold the latter in gripping engagement with the rod.

In testimony that I claim the foregoing as my own, I have hereto affixed my signature in the presence of two witnesses.

WILLIAM W. SWEETLAND.
